CLAIM

The ornamental design for a neo-natal intubation swivel connector for a catheter, as shown and described.

DESCRIPTION

FIG. 1 is an isometric view of the neo-natal intubation swivel connector for a catheter of the instant invention; FIG. 2 is a top view of the neo-natal intubation swivel connector for a catheter of the instant invention; FIG. 3 is a bottom view of the neo-natal intubation swivel connector for a catheter of the instant invention; FIG. 4 is a side view of the neo-natal intubation swivel connector for a catheter of the instant invention. The opposite side view is identical; and, FIG. 5 is a cross-sectional view of the neo-natal intubation swivel connector for a catheter, taken along the line 5—5 of FIG. 2.

FIG. 1

FIG. 2

FIG. 5

FIG. 4

FIG. 3
